(57) **CLAIM**

The ornamental design for a display device with graphical user interface, as shown and described.

DESCRIPTION

FIG. 1 is a front view of a first image in a sequence for a display device with graphical user interface;
FIG. 2 is a front view of a second image thereof; and,
FIG. 3 is a front view of a third image thereof.

The broken lines in the figures showing a display screen, electronic device, and portions of the graphical user interface are for illustrative purposes only and form no part of the claimed design.

The appearance of the animated sequence sequentially transitions between the images shown in FIGS. 1-3. The process or period in which an image transitions to another forms no part of the claimed design.
